UNITED STATES PATENT OFFICE

EDOUARD BELIN, OF PARIS, FRANCE

DEVICE FOR RECORDING DOCUMENTS TRANSMITTED BY RADIO

Application filed November 2, 1929, Serial No. 404,458, and in France November 10, 1928.

In my two French Patents Nos. 673,695 and 678,622, respectively of August 22 and November 6, 1928, I described an assembly of devices which allowed receiving stations, 5 whether a subscriber or not, to receive on a recording cylinder by electro-chemical means, documents transmitted by a radio broadcasting station by means of variations in current or radio-electric transmission. In 10 the said patents, the surface for recording is carried by a cylinder and must be changed each time a transmission is terminated.

According to my present invention the recording takes place in a continuous manner 15 and not on individual papers, but on a sheet which is displaced in a continuous way from a containing roller and either rewound on a rewinding roller or accumulated in a receptacle, basket, or similar object, the remaining parts of the device being unchanged.

The sensitized paper which was used in the two patents above referred to and in my French patent of addition No. 36,297 of 25 October 30, 1927, is therefore wound on a bobbin from which it unrolls freely over a series of suitable guides and then forms a tubular shape about a recording cylinder whose axis is parallel to the direction of 30 movement of the band of paper which cylinder remains stationary and acts as a platen.

From the cylinder the paper moves toward the outlet of the apparatus and through analogous guides its plane form is restored 35 thereto after which it passes between rollers or drums which draw the same and impart displacement thereto for either rewinding or for allowing to accumulate freely. This movement as before stated is continuous.

40 Consequently, since the recording cylinder is stationary, the recording can be brought about in a plane perpendicular to the axis of said cylinder. As a result of this arrangement successive spirals take place as in the 45 patents above pointed out. For producing this result two means are possible, to wit, the rotation of the tracing stylus about the recording cylinder or the rotation of the paper being displaced linearly in which case the whole band of paper is rotated about the axis

of the recording cylinder. In either case the rotation of either the stylus or the paper taken in combination with the linear displacement of the paper in either case, the stylus is caused to advance in a helicoidal 55 manner along the cylinder or vice versa when the stylus remains stationary in space.

My invention is based upon these principles above outlined and will now be described in detail with reference to the accompanying drawing forming a part of this specification and in which—

Fig. 1 is a conventional diagram of my invention illustrating an embodiment in which the stylus is rotated;

65

Fig. 2 is a similar view illustrating another embodiment of my invention in which the paper sheet is rotated and the stylus remains stationary;

Fig. 3 is a sectional detail along the line 70 3—3 of Fig. 2; and

Fig. 4 is a sectional detail along the line 4—4 of Fig. 2.

Referring to the drawing more in detail and particularly to Fig. 1, the paper 1 is unwound from a bobbin 2 and preferably wound and drawn along by a second bobbin 3, but in some cases may be drawn along by rollers and allowed to accumulate freely, such rollers not being shown on the drawing. By means 75 of gradually decreasing arcuate guides 4, 5 and 6, the strip of paper 1 is given a tubular shape about a cylinder 7 which is stationary. Analogous guides 4', 5' and 6' arranged to gradually increase outwardly from the other 85 end of the cylinder restore the flat form to the paper strip 1.

Disposed in a plane perpendicular to the axis of cylinder 7 is a ring 8 suitably guided and adapted to be rotated about the cylinder 90 7 by means of a worm meshing with ring 8 as shown at 9. The pinion 9 is adapted to be given a synchronized movement with respect to the transmitter as more fully described in the patents above referred to. Within the ring 8 is secured a stylus P for recording to which leads one of the wires of the circuit as more fully explained in the 95 patents above called to attention. From the foregoing it will be obvious that by the com- 100

bination of the circle described by the stylus in the same plane and the linear displacement of the paper strip, recording will take place on the said strip in spirals in continuous manner.

5 Adverting to Figs. 2 to 4, the bobbins 2 and 3 and the paper guides 4, 5 and 6 and 4', 5' and 6' are all mounted in a rotary frame 10 adapted to be driven by a suitable motor M about the axis of cylinder 7 subjected to 10 a synchronizing movement. The ring 8 is rotatably mounted in the frame 10 and maintained stationary either by its own weight, or preferably by the attraction of a magnet E, or both these expedients. Within the 15 ring 8 is mounted the stylus P as before.

From the foregoing it will be obvious that the strip of paper beneath the stylus is given a helicoidal displacement and here again the recording will take place in the form of 20 spirals.

While I have described what I deem to be the preferred forms of my invention I do not wish to be limited thereto as there might be changes made in the construction and arrangements of the parts without departing from the spirit of the invention as comprehended within the scope of the appended 25 claims.

30 Having described my invention what I claim as new and desire to secure by Letters Patent is:

1. In a device for recording documents transmitted by radio the combination of a 35 paper strip, means for imparting linear displacement to said strip, means for forming a cylindrical shape of a portion of said strip, a rotary ring surrounding said cylindrical portion, a stylus in said ring for said strip, and a worm for imparting rotary motion to 40 said ring.

2. In a device for recording documents transmitted by radio the combination of a 45 paper strip, means for imparting linear displacement to said strip, a stationary cylinder adapted to receive said strip, a plurality of decreasing arcuate guides adapted to curve said strip over said cylinder, a second plurality of arcuate guides of increasing size 50 adapted to allow said paper to take a plane shape, a stylus for said strip, and means for producing relative rotary movement between said stylus and the cylindrical portion of 55 said strip.

60 3. In a device for recording documents transmitted by radio the combination of a paper strip, means for imparting linear displacement to said strip, a stationary cylinder adapted to receive said strip, a plurality of 65 decreasing arcuate guides adapted to curve said strip over said cylinder, a second plurality of arcuate guides of increasing size adapted to allow said paper to take a plane shape, a stylus for said strip, and means for 70 imparting rotary motion to said strip.

4. In a device for recording documents transmitted by radio the combination of a paper strip, means for imparting linear displacement to said strip, a stationary cylinder adapted to receive said strip, a plurality of decreasing arcuate guides adapted to curve 75 said strip over said cylinder, a second plurality of arcuate guides of increasing size adapted to allow said paper to take a plane shape, a stylus for said strip, and means for imparting rotary motion to said stylus about said cylindrical portion.

In testimony whereof I hereunto affix my signature.

EDOUARD BELIN.
